UNITED STATES PATENT OFFICE.

HORACE MANSFIELD, OF YONKERS, NEW YORK, ASSIGNOR OF ONE-HALF TO
RICHARD R. MANSFIELD, OF YONKERS, NEW YORK.

ORTHOPEDIC SHOE ARCH SUPPORT.

Application filed February 3, 1927. Serial No. 165,634.

This invention relates to orthopedic arch supports for correcting fallen arches and for other purposes, and more particularly to supports for attachment to the shank of shoes.

5 One object of the invention is to provide an apparatus or device of this kind which may be easily attached to ordinary shoes.

Another object of the invention is to provide an apparatus or device of this kind 10 which will support or strengthen the shank of the shoe without destroying its flexibility.

Another object of the invention is to provide an apparatus or device of this kind 15 which may be adjusted for different conditions of arches, form improvement and change of condition of the arch, and to compensate for change in the shoe from use.

Other objects of the invention are to improve generally the simplicity and efficiency 20 of such devices and to provide a device or apparatus of this kind which is helpful, durable and reliable and slight in use, economical to manufacture, and which will not injure the shoe.

25 Still other objects of the invention will appear as the description proceeds; and while herein details of the invention are described and claimed, the invention is not limited to these, since many and various changes may 30 be made without departing from the scope of the invention as claimed in the broader claims.

The inventive features for the accomplishment of these and other objects are shown 35 herein in connection with two improved arch supports which, briefly stated, include a plate adapted to be secured to a shoe sole and having a downturned rear end flange having a perforation receiving a bolt. One form of 40 the invention has a band adapted to go around the shoe heel and having end portions near said perforation provided with registering threaded bores. The bolt is received in said perforation and bores and holds the flange 45 and said ends adjustably connected so as to form an adjustable brace or strut for the shank of the shoe. In another form of the invention, the shoe has a bore passing longitudinally through the heel and receiving an 50 internally threaded bushing having an outwarded flange at the rear end. The bolt is disposed in said perforation and bushing and holds the plate and said ends connected.

In the accompanying drawing, showing by

way of example, two of many possible embodiments of the invention,

55 Fig. 1 is a fragmental side elevation showing one form of the support attached to a shoe;

Fig. 2 is a bottom view of the device as in 60 Fig. 1;

Fig. 3 is an erect longitudinal vertical sectional view, partly in elevation, and on an enlarged scale, showing the arch support detached, the section being taken on the line 65 3-3 of Fig. 2, looking in the direction of the arrow of said line;

Fig. 4 is a fragmental side elevation showing another form of the invention; and

Fig. 5 is a fragmental rear end elevation 70 showing the form of Fig. 4.

My improved arch support of Figs. 1 to 75 3 is shown in connection with a shoe 10, and comprises a sole plate 11, a heel band 12 and a connecting bolt 13.

The sole plate 11 is connected to the sole of the shoe by rivets 15 and has its forward edge-portion 16 laterally extended nearly across the sole of the shoe just behind the ball of the foot and somewhat forwardly angularly advanced at the outer part 17 of the sole to conform to the shape of the foot.

The rear part of the plate comprises a rearwardly extended narrow longitudinal flat portion 20 engaging the sole and having downturned side flanges 21 approximately triangular in shape and an end flange 22 joining an edge of each side flange to form a forwardly open rearwardly closed bolt-head housing and provided with a central perforation receiving the bolt 13.

The heel band 12 is preferably slightly downwardly forwardly inclined and disposed around the heel of the shoe near the upper part thereof, and comprises a curved 95 rear, or intermediate, portion 25 forcing its upper rear edge to dent into the rear of the heel to help hold the band in place. The portion 25 conformably engages the rear and side faces of the heel and merges into inwardly inclined spring portions 26 joining the ends of the curved portion and inclining inwardly and rearwardly toward said housing, their overlapping end portions 27, 28 being provided with registering threaded bores. 100

The bolt 13 has its rear end 30 threaded and received in said threaded bores of the overlapping ends 27, 28; and its front end is pro-

vided with a bolt head 31 disposed in said housing and engaged against said end flange 22. Said head is provided with a tool receiving slot whereby a tool may be disposed in the forwardly open part of the housing to engage said slot, thereby to turn the screw and tension the support for strengthening the shank without destroying its flexibility, or on further tensioning to adjustably raise the shank to conform to different feet or to compensate for loss of stiffening of the shoe through use, or to conform the shoe to change in the foot as the foot is improved by use of the support.

15 A lock nut 32 on the threaded end of the bolt and engaging one of said overlapping ends locks the bolt against loss and holds the support in adjustment.

The various parts of the device may be 20 made of steel or other suitable metal, which may be rendered rust-proof by tinning or the like.

In the form of invention of Fig. 4, the shoe heel 33 has a slightly downwardly inclined bore 34 passing through the heel near its 25 main axis. This bore receives an internally threaded bushing 35 having an out-turned flange 36 at the rear end to form a head engaging the rear of the shoe heel. The bolt 13 is disposed in said perforation of the rear flange 22 and said threaded bushing and 30 holds the plate and said ends connected as in the other form of the invention.

The operation of the other support is 35 obvious from the foregoing. The support is applied as shown and the bolt tightened until the shank of the shoe will be held at the proper height. While thus held, the shank of the shoe is quite flexible due to the displacement from its normal position when the bolt 13 is tightened, and may be flexed downwardly against the action of the spring portion 26, or may be freely flexed up or twisted. This flexibility permits the arch and muscles 40 of the foot to be massaged and exercised 45 while walking.

Increased tension of the bolt increases the amount of support to suit the strength of the foot; and as the strength increases, the support may be lessened.

50 If the arch of the foot is too low, the bolt may be tensioned to raise the arch slightly at first, and then more as the arch has become accustomed to the slight increase.

55 When the shank of the shoe begins to lower from loss of stiffness of the shoe or use, the shank may be brought up to normal by tensioning the bolt.

I claim as my invention:

60 1. An arch support comprising a member adapted to be secured to a shoe sole; a member having a resilient portion adapted to embrace a shoe heel; and a device adjustably connecting said members.

65 2. An arch support comprising a member

adapted to be secured to the sole of a shoe; a band including overlapping spring portions adapted to be secured around the heel of the shoe; and a device connecting said member and band.

70 3. An arch support comprising a plate adapted to be secured to a shoe sole and having a member having a perforation; a band adapted to go around the shoe heel and having end portions near said perforation provided with registering threaded bores; and a bolt in said perforation and bores and holding said member and said ends against separation.

75 4. An arch support comprising a member adapted to be secured to a shoe sole; a member adapted to be secured to a shoe heel; said second member having a spring clamping means connecting said members.

80 5. An arch support comprising a member adapted to be secured to a shoe sole; a springy member adapted to embrace a shoe heel; and a device connecting said members.

85 6. An arch support comprising a member adapted to be secured to a shoe sole; a band adapted to be secured around a shoe heel and having a forward spring portion and a device connecting said member and portion.

90 7. An arch support comprising a member adapted to be secured to the sole of a shoe; a heel band adapted to be arranged around the shoe heel with its upper rear edge denting into the upper rear part of the heel; said band having overlapping end portions near 95 said perforation provided with registering threaded bores; and a threaded bolt in said bores and attached to said member holding the flange and said ends against separation.

100 8. An arch support comprising a plate adapted to be secured to the sole of a shoe and provided with an attachment member; a member having a forward spring portion adapted to embrace the heel of the shoe; and a device connecting said members.

105 9. A shoe-arch support comprising a sole plate adapted to be secured to a shoe sole and have its forward portion laterally extended just behind the ball of the foot; the rear part of the plate being formed into an attachment member; a member having a forward spring portion adapted to embrace the shoe heel; and a device connecting said members.

110 10. An arch support comprising a plate adapted to be secured to a shoe sole, the rear of the plate comprising a longitudinal portion having downturned side and rear flanges, the latter being provided with a perforation; a member adapted to embrace the shoe heel provided with a threaded perforation; and a bolt in said perforations provided with a head engaged against the inner face of said end flange.

115 11. A shoe-arch support comprising a sole plate adapted to be secured to a shoe sole and have its forward portion laterally extended 120

125 130

just behind the ball of the foot; the rear of the plate comprising a longitudinal portion having downturned side and rear end flanges, the latter being provided with a perforation; a heel band adapted to be arranged around the shoe heel with its upper rear edge denting into the heel; said band having overlapping end portions near said perforation provided with registering threaded bores; and a bolt in said perforation provided with a head engaged against the end flange.

12. An arch support comprising a plate adapted to be secured to a shoe sole and having a downturned rear end flange having a perforation; a slightly downwardly and forwardly inclined metallic heel band adapted to be disposed around the heel of the shoe near the upper part thereof and comprising a curved rear or intermediate portion forcing its upper rear edge to dent into the rear of the heel, and conformably engaging the rear and side faces of the heel, inwardly inclined spring portions joining the curved portion and pointing inwardly and rearwardly, and overlapping end portions provided with registering threaded ends; and a bolt in said perforation and bores and holding the flange and said ends against separation.

13. An arch-support for a shoe, said support comprising a sole plate adapted to be riveted to the sole of a shoe and have its forward edge-portion laterally extended nearly across the sole of the shoe just behind the ball of the foot and somewhat forwardly and angularly advanced at the outer part of the sole to conform to the foot; the rear part of the plate comprising a rearwardly extended narrow longitudinal flat portion adapted

to engage the sole and having downturned triangular side flanges and an end flange joining an edge of each side flange to form a forwardly open, rearwardly closed bolt-head housing and provided with a central perforation; a band adapted to go around the shoe heel and having end portions near said perforation provided with registering threaded bores; and a bolt in said perforation and bores and holding the end flange and said ends connected.

14. An arch support comprising a plate adapted to be secured to a shoe sole and having a downturned side and rear end flanges forming a housing, the end flange having a perforation; a band adapted to go around the shoe heel and having end portions near said perforation provided with registering threaded bores; a bolt in said hole having its rear end threaded and received in said bores and its front end provided with a bolt head in said housing engaged against said end flange and provided with a tool receiving slot whereby a tool may be disposed in the forwardly open part of the housing to engage said slot thereby to tension the support for strengthening the arch without destroying its flexibility, or on further tensioning to adjustably raise the arch to compensate for loss of stiffening of the shoe through wear; and a lock nut on the threaded end of the bolt and engaging one of said overlapping ends to hold the support in adjustment.

Signed at New York, in the county of New York and State of New York, this 2nd day of February, A. D. 1927.

HORACE MANSFIELD.
